UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed December 8, 1921. Serial No. 520,872.

This invention relates to water tube boilers of the type that comprise oppositely-inclined banks of water tubes arranged at opposite sides of a substantially A-shaped combustion chamber.

In boilers of the general type referred to it has heretofore been the usual practice to arrange a water drum, a water box or a refractory structure at the apex of the combustion chamber so as to divide the fire gases into two streams and direct said streams into the separate tube banks at the opposite sides of the combustion chamber and also to prevent the lower end portions of the upper headers of the respective banks from burning out on account of the accumulation of sediment inside of same.

One object of my invention is to provide a boiler of the general type referred to, in which the upper headers of the respective banks form the apex of the combustion chamber between said banks and are of such design that sediment cannot accumulate in the portions of said upper headers which are subjected to radiant heat in sufficient quantities to cause said headers to burn out. By constructing the boiler in this manner I materially reduce the cost of manufacture of the boiler, due to the elimination of a separate part such as a water drum, a water box or a refractory structure, and also the elimination of an arch or other sustaining means for carrying said separate part.

Another object of my invention is to provide a boiler of the general type referred to which is of such design that the circulation of the water through the tubes and headers of the respective banks is materially increased, thereby making it possible to run the boiler at a higher capacity than is usual in boilers of this design.

And still another object is to provide a boiler of the general type referred to that is equipped with a novel form of baffling.

To this end I have devised a boiler that comprises two oppositely-inclined banks of water tubes arranged at opposite sides of a substantially A-shaped combustion chamber, and header structures at the upper ends of said banks provided with co-operating

portions that form the apex of the combustion chamber and which are combined with the bottom tubes or radiant heat tubes of the banks in such a way as to prevent sediment from collecting in the portions of said upper headers that are exposed to radiant heat, in such quantities as to cause said headers to burn out. Preferably the header structure at the upper end of each tube bank is provided with a number of spaced portions that extend transversely of the boiler at the upper end of the combustion chamber, and the portions referred to of the header structures of the respective banks are arranged in interlocking engagement or in dove-tail relation with each other so that they act collectively to form the apex of the combustion chamber. The spaced portions of each header structure, in addition to being directly connected to the upper ends of some of the bottom tubes or radiant heat tubes of the bank of which the header structure forms a part, are also directly connected to the upper ends of some of the bottom tubes or radiant heat tubes of the other bank, thus causing the water that circulates upwardly through some of the radiant heat tubes of the bank at one side of the combustion chamber to cross over and enter the header structure of the other bank, and the water that circulates upwardly through some of the radiant heat tubes of said other bank to cross over and circulate upwardly through the header structure of the bank first referred to. The header structures are preferably so arranged that each header structure forms practically a continuation in a substantially straight line of some of the radiant heat tubes of the bank on the other side of the combustion chamber, thereby providing upflow passageways of such length as to insure the water circulating upwardly through same at a materially higher velocity than is attained in a boiler of the kind in which the water makes an abrupt right-angular turn when it reaches the upper end of the bottom tubes or radiant heat tubes of each tube bank. Accordingly, in my improved boiler the water will circulate through the portions of

the upper headers that form the apex of the combustion chamber in such a way as to prevent sediment from collecting in said portions in sufficient quantities to cause the 5 headers to burn out. Moreover, as each of the spaced portions of the header structures has two oppositely-inclined, radiant heat tubes connected to same, there is only a relatively small surface of said portion 10 that is subjected to the direct action of the fire gases. The increased upward circulation through relatively long water passage-ways not only tends to prevent sediment 15 from collecting in the lower portions of the upper headers, but it also increases the circulation through the entire boiler in such a way as to make it possible to run the boiler at a higher capacity than is the usual practice. In other words, in my improved boiler 20 the water which circulates upwardly through some of the radiant heat tubes of each bank does not make an abrupt or right-angular turn when it reaches the upper ends of said tubes, but, on the contrary, continues 25 to flow in the same general direction upwardly through the header structures of the boiler, thereby causing the water that circulates upwardly through the header structures to obtain such a high velocity that the circulation of the water through all of the tubes of each bank is materially increased.

Preferably sectional headers are used at the upper ends of the tubes of the respective banks, and the portions of the header structures previously referred to that co-operate with each other to form the apex of the combustion chamber are obtained by building up each header structure from alternately arranged long and short headers, the 40 lower end portions of the long headers of the respective banks dove-tailing with each other so that they act collectively to form the apex of the combustion chamber.

The baffling that I prefer to use in my boiler differs from the baffling used in prior boilers provided with an A-shaped combustion chamber, in that each tube bank is provided with a substantially vertically-disposed first baffle that crosses the tubes at such an angle that the first pass has an inlet of materially greater area than its exit and an inclined second baffle which crosses the tubes at such an angle that the second pass has an inlet of materially greater area than its exit.

Figure 1 of the drawings is a vertical longitudinal sectional view of a boiler constructed in accordance with my invention.

Figure 2 is a cross sectional view of the tube bank at the left hand side of the combustion chamber, taken on the line 2—2 of Figure 1, looking in the direction indicated by the arrows; and Figure 3 is a fragmentary view, showing one of the long upper headers of the lefthand bank and one of

the short upper headers of the right hand bank.

Referring to Figures 1 and 2 of the drawings, A and B designate two oppositely-inclined banks of water tubes arranged at opposite sides of a substantially A-shaped combustion chamber C, 1 and 2 designate sectional headers that are arranged at the upper ends of the tubes of the bank A and 3 designates sectional headers arranged at the lower ends of the tubes of the bank A. The upper headers 1 and 2 are of different length and are arranged so that the long headers 2 will be positioned between the short headers 1, as shown in Figure 2, thus forming an upper header structure provided at its lower end with a plurality of spaced portions 2^a that extend transversely of the combustion chamber C. The bank B is provided with an upper header structure of the same kind as the upper header structure of the bank A, and composed of long sectional headers 4 arranged in alternate relation with short headers 40, one of which is shown in Figure 3, each of the long headers 4 being provided at its lower end with a portion 4^a, as shown in Figures 1 and 2. The portions 4^a of the upper header structure of the bank B are arranged in dove-tail relation with the portions 2^a of the upper header structure of the bank A so that said portions 4^a and 2^a act collectively to form the apex of the combustion chamber C. The bank B is provided with lower sectional headers 5. The bottom tubes or radiant heat tubes 6 of the bank A are connected at their upper ends to the upper header structures of both banks. Thus, as shown in Figure 2 and partly in Figure 1, one-half of the bottom tubes 6 of the bank A are connected at their upper ends to the portions 4^a of the upper header structure of the bank B and the remaining bottom tubes 6 of the bank A are connected at their upper ends to the depending portion 2^a of the upper header structure of the bank A, the tubes 6 that are connected to the header portions 4^a entering the ends of said portions, as shown in Figure 1, and the tubes 6 that are connected to the header portions 2^a entering the 100 sides of same, as shown in Figure 2, wherein in the ends of the portions 4^a have been slightly shaded so as to more clearly distinguish same from the sides of the header portions 2^a. The bottom tubes or radiant heat tubes 7 of the bank B have their upper ends connected to the upper header structures of the respective banks in the same manner, namely, one-half of the tubes 7 are connected at their upper ends to the 105 sides of the header portions 4^a and the remainder are connected at their upper ends to the ends of the header portions 2^a of the bank A.

Each bank is provided with a transverse 110

steam-and-water drum Δ which is connected by means of downcomers Σ with the bottom header structure of the bank of which it forms a part, and in the form of my invention illustrated in Figure 1, each bank is equipped with a steam superheater Γ that is arranged preferably in a space in the bank formed by dividing the tubes of the bank into a lower group and an upper group, the superheater of each bank being formed preferably by a number of substantially U-shaped tubes arranged parallel to the water tubes of the bank with which the superheater is associated, and transverse headers δ combined with said U-shaped tubes in the usual manner.

The baffling of my improved boiler is different from the baffling that is generally used in boilers of the kind to which my invention relates, and is so constructed that each bank is provided with a first pass having an inlet of materially greater area than its exit, and a second pass whose inlet is of materially greater area than its exit. As shown in Figure 1, each bank of the boiler is provided with a substantially vertically-disposed transverse first baffle 9 that crosses the tubes of the bank at such an angle that the inlet of the first pass of the bank is of greater area than the exit of the first pass. A second transverse baffle 10 is arranged in each tube bank at such an angle with relation to the first baffle 9 of the bank as to form a second pass whose inlet is of materially greater area than its exit. When the boiler is in operation the fire gases circulate through the respective banks in the manner indicated by the arrows in Figure 1 and escape through uptakes 11 which lead from the lower ends of the banks. It is immaterial what type of stoking apparatus the boiler is equipped with. Therefore, I have illustrated the boiler shown in Figure 1 as being equipped with a conventional under feed stoker that comprises grates 12 to which fuel is supplied from hoppers 12^a arranged at the lower ends of chutes or troughs 12^b down which the fuel is conducted to the hoppers.

As previously stated, the apex of the combustion chamber C of the boiler is formed by the co-operating interlocking portions 2^a and 4^a of the long headers at the upper ends of the respective banks. Therefore, such a boiler can be manufactured at a low cost, as it is not necessary to arrange a refractory structure or a water drum or water box separate and distinct from the header structures at the upper end of the combustion chamber. In view of the fact that each of the header portions 2^a and 4^a has two oppositely-inclined water tubes connected to same, there is only a relatively small surface of each of said portions that is subjected to radiant heat. The fact, however, that said header portions are combined with the bottom tubes or radiant heat tubes of the respective banks in such a manner that they virtually form straight continuations of the water tubes that are connected to the ends of said portions, eliminates the possibility of sediment collecting in said portions in sufficient quantities to cause them to burn out. When the boiler is in operation the water that circulates upwardly through part of the radiant heat tubes 6 of the bank A continues to flow upwardly in the same general direction, after reaching the upper ends of said tubes, due to the fact that the long upper headers of the bank B are arranged in substantially longitudinal alignment with said tubes. Accordingly, the water that circulates upwardly through the tubes 6 referred to will attain such a high velocity, in traveling upwardly through the long headers of the bank B , that it greatly increases the circulation in the entire bank B . Likewise, the water that circulates upwardly through those radiant heat tubes 7 of the bank B whose upper ends are connected to the long upper headers of the bank A will attain a high velocity, in traveling upwardly through said long headers, thus materially increasing the circulation in the entire bank A . While I prefer to build the upper header structure of each bank from alternately arranged short and long sectional headers, my broad idea contemplates the use of any kind of upper header structures for the respective banks that are provided with spaced interlocking or dove-tail portions that act collectively to form the apex of a substantially A-shaped combustion chamber and which are combined with the radiant heat tubes or bottom tubes of the banks at the opposite sides of said combustion chamber in such a manner that the upper header structures virtually form continuations in a substantially straight line of some of the radiant heat tubes, and thus produce a so-called A-type boiler in which the water that circulates upwardly through some of the radiant heat tubes of each bank can continue its upflow uninterruptedly, after reaching the upper ends of said tubes. As previously stated, cross connecting the upper header structures of the respective banks together in this manner prevents the accumulation of sediment in the portions of the upper header structures that are subjected to the direct action of the fire gases and it increases the entire circulation of the boiler to such an extent that it is possible to run the boiler at a higher capacity than is the usual practice.

Having thus described my invention, what I claim as new and desire to secure by Letters Patent is:

1. A boiler, comprising oppositely-inclined banks of superimposed water tubes arranged at opposite sides of a substantially A-shaped combustion chamber, each of said banks hav-

ing radiant heat tubes, a steam-and-water drum associated with each of said banks, and a header structure at the upper end of each of said banks, disposed at an angle to the tubes of same and having its lower end portion communicating with some of the radiant heat tubes of the other bank and arranged in substantially longitudinal alignment therewith so as to virtually form a continuation in a straight line of said radiant heat tubes.

2. A boiler provided with banks of oppositely-inclined superimposed water tubes arranged at opposite sides of a substantially A-shaped combustion chamber, each of said banks having radiant heat tubes, a steam-and-water drum associated with each of said banks, a header structure at the upper end of each bank disposed at an angle to the tubes of same and arranged in substantially longitudinal alignment with the radiant heat tubes of the other bank, and means whereby the water that circulates upwardly through some of the bottom tubes of each bank can continue its upward circulation uninterruptedly through the header structure of the other bank.

3. A boiler, comprising two oppositely-inclined banks of superimposed water tubes arranged at opposite sides of a substantially A-shaped combustion chamber and each provided at its upper end with a header structure disposed at substantially right angles to the tubes of the bank, said header structures being equipped with co-operating portions that form the apex of said combustion chamber and some of the bottom row of tubes of each bank being connected to the lower end of the header structure of the other bank so as to cause the water in said tubes to circulate uninterruptedly through said header structure.

4. An A-type boiler, comprising oppositely-inclined banks of superimposed water tubes arranged at opposite sides of a combustion chamber common to both of said banks, a header structure at the upper end of each bank, and portions at the lower ends of said header structures arranged in staggered relation so as to form the apex of the combustion chamber, the portions referred to of each header structure being directly connected to some of the bottom tubes of the bank of which it forms a part and also directly connected to some of the bottom tubes of the other bank.

5. An A-type boiler provided with oppositely-inclined banks of superimposed water tubes, and header structures at the upper ends of said banks provided at their lower ends with spaced portions arranged so that the portions on one header structure are positioned between the portions of the other header structure, some of the bottom tubes of each bank being connected to the header

portions of the bank of which said tubes form a part and the remaining bottom tubes being connected to the header portions of the other bank.

6. An A-type boiler, comprising oppositely-inclined banks of superimposed water tubes, each of said banks having radiant heat tubes, and header structures at the upper ends of said banks provided at their lower ends with extensions that are arranged in substantially dove-tail relation, each of said extensions being directly connected to a radiant heat tube or bottom tube of each bank.

7. An A-type boiler provided with oppositely-inclined banks of superimposed water tubes, each of said banks having radiant heat tubes, and header structures at the upper ends of said banks provided at their lower ends with extensions arranged in substantially staggered relation and combined with the radiant heat tubes of the banks in such a manner that some of the radiant heat tubes of each bank enter the sides of the extensions on the header structure of that particular bank and some of the radiant heat tubes of the other bank enter the ends of said extensions.

8. A boiler, comprising oppositely-inclined banks of superimposed water tubes, each of said banks having radiant heat tubes, and a header structure at the upper end of each bank composed of long and short headers arranged in alternate relation, the long headers being directly connected to some of the radiant heat tubes of the bank of which said headers form a part and also directly connected to some of the radiant heat tubes of the other bank.

9. A boiler provided with oppositely-inclined banks of superimposed water tubes arranged at opposite sides of a substantially A-shaped combustion chamber, each of said banks having radiant heat tubes, and long and short sectional headers arranged at the upper ends of said banks in such a manner that the lower end portions of the long headers form the apex of said combustion chamber, each of said long headers being directly connected to one of the radiant heat tubes of the bank of which said header forms a part and also directly connected to one of the radiant heat tubes of the other bank.

10. An A-type boiler, comprising oppositely-inclined banks of superimposed water tubes, each of said banks having radiant heat tubes, and a header structure at the upper end of each bank composed of a number of short sectional headers arranged between a number of long sectional headers and both disposed at an angle to the tubes of the bank, the long headers of each bank communicating with some of the bottom tubes of the other bank and arranged in substantially longitudinal alignment therewith so as to virtually form a continuation in a substan-

tially straight line of same and also act collectively to form the apex of the combustion chamber.

11. A boiler provided with oppositely-inclined banks of superimposed water tubes arranged in proximity to a combustion chamber common to both banks, each of said banks having radiant heat tubes, and sectional headers at the upper ends of said banks,

some of the headers of each bank being provided with portions that co-operate with similar portions on headers of the other bank to form the apex of the combustion chamber and each of said portions being directly connected to the upper ends of radiant heat tubes located at opposite sides of the combustion chamber.

ALFRED COTTON.
